UNITED STATES PATENT OFFICE.

JOHN FINNEGAN, OF PHILADELPHIA, PENNSYLVANIA.

DESIGN FOR A SAUCEPAN-HANDLE.

SPECIFICATION forming part of Design No. 16,053, dated April 21, 1885.

Application filed March 14, 1885. Term of patent 14 years.

To all whom it may concern:

Be it known that I, JOHN FINNEGAN, a citizen of the United States, residing at Philadelphia, in the county of Philadelphia and State of Pennsylvania, have invented a certain new Design for Saucepan-Handles; and I do hereby declare the following to be a full, clear, and exact description of the same, reference being had to the accompanying drawing, which forms part of this specification, in which the figure is an elevation.

My design relates particularly to that part of the handle which is grasped in lifting, &c., and which is marked A, the shank or narrower portion below, to which the fastening lug or ear C is attached, being marked B. The handle is concavo convex in transverse section, and the part A has ornamental interstices or openings, as shown. The upper one of these (marked a) is a flattened oval; and there are two circular or approximately circular openings, b and c, respectively having cross-bars, the bars in the opening b forming the letter N reversed, and the bar in the opening e being a straight bar with a diamond at its middle. There are two other openings, d and e, like each other, each one having two parallel sides with top and bottom V-shaped ends or edges, and with cross-bars the same as in the opening e.

The narrow part or shank C of the handle has a central convex rib with intaglio marks, as shown, which may be varied without affecting the design.

What I claim as my invention is-

The design for a saucepan-handle herein described and shown, consisting of the concavo-convex part A, having a flattened oval opening, a, and the openings b, c, d, and e, with cross-bars, as set forth.

In testimony that I claim the foregoing I have hereunto set my hand this 3d day of March, 1885.

JOHN FINNEGAN.
